UNITED STATES PATENT OFFICE.

WILLIAM C. JACOB, OF DALLAS, IOWA.

WINDMILL.

SPECIFICATION forming part of Letters Patent No. 234,580, dated November 16, 1880.

Application filed July 24, 1880. (No model.)

To all whom it may concern:

Be it known that I, WILLIAM C. JACOB, of Dallas, in the county of Marion and State of Iowa, have invented certain new and useful 5 Improvements in Windmills; and I do hereby declare that the following is a full, clear, and exact description of the invention, which will enable others skilled in the art to which it appertains to make and use the same, reference 10 being had to the accompanying drawings, which form a part of this specification, and in which—

Figure 1 is a plan or top view of my improved windmill. Fig. 2 is a vertical section 15 laid through the broken line xx in Fig. 1, and Fig. 3 is a perspective view.

Similar letters of reference indicate corresponding parts in all the figures.

My invention contemplates improvements 20 in vertical windmills, &c.; and it consists of a revolving frame carrying vanes hinged or pivoted therein, with check ropes or chains, and adapted to close when in the wind and to open when out of the wind, substantially as herein- 25 after more fully set forth.

In the accompanying drawings, A marks an upper, and A' a lower, head, suitably secured together, which constitute the frame carrying the vanes, and which said heads are journaled 30 upon a central shaft.

B B are the vanes, preferably oblong or rectangular in form, and hinged or pivoted at their upper and lower ends, respectively, to the upper and lower heads in sections of two or 35 more, each section of two or more vanes or wings being arranged radially with relation to the central shaft, and with their adjacent edges

adapted to meet and form, when presented to the wind, a continuous unbroken surface to catch the full force of the wind, which drives 40 or revolves the wheel. Rubber cushions or stops *a a*, in practice, check the closing action of the individual wings or vanes, while their opening action is checked by ropes or chains *b*. These vanes or wings may, one or more of 45 each section, be presented to the action of the wind, or all of each section, according to the amount of speed required. By increasing the number of vanes of each or of one or more sections, the power of the wheel or mill can 50 be proportionately increased, and its driving capacity be correspondingly augmented.

C C are shutters fastened to and closing one side of a four-sided frame or pen inclosing the vane-frame and vanes. The shutters are 55 designed to shield and break the great force of the wind, during a storm, with relation to the vanes.

Having thus fully described my invention, I claim and desire to secure by Letters Patent 60 of the United States—

In a horizontal windmill, the combination, with the radial arms A A', of the pivoted wings or vanes B B, arranged in pairs between said arms, and each pair flexibly connected to 65 each other and to the central shaft by cords or chains *b*, as set forth.

In testimony that I claim the foregoing as my own I have hereto affixed my signature in presence of two witnesses.

WILLIAM C. JACOB.

Witnesses:

JOHN M. JONES,
C. E. NORRIS.
